Attorney.

UNITED STATES PATENT OFFICE.

JOHN BUSS, OF FREEPORT, ILLINOIS.

EARTH-EMBEDDED FLOWER HOLDER.

Application filed June 16, 1922. Serial No. 568,728.

To all whom it may concern:

Be it known that I, JOHN BUSS, a citizen of the United States, and resident of Freeport, in the county of Stephenson and State 5 of Illinois, have invented certain new and useful Improvements in Earth-Embedded Flower Holders, of which the following is a specification, reference being had therein to the accompanying drawing.

- 10 This invention relates to flower holders, especially such as are to be sunk or embedded in the earth, in cemeteries, for example, and so not subject to upsetting by winds. The construction is such that the device 15 may hold flowers at some distance above the ground's surface, so that rains will not spray them with earthy matter, or may hold them not so raised, or when not in use may itself be flush with the ground and not interfere with mowing, raking, or walking upon 20 the entire surface. The holder is adapted to contain a removable water receptacle, to hold the flowers M in desired arrangement, and to resist withdrawal from the earth, and 25 at the same time to be very simple in construction, durable, and almost invisible when not in use. Preferably, the device consists of two tubular telescoping parts, both downwardly open so that water will 30 not accumulate there in, the outer part having earth engaging projections which resist vertical movement, and the inner part arranged for a limited upward movement with respect to its companion, and for locking 35 in raised position.

In the accompanying drawings,

Fig. 1 is a side view of the device sunk in the ground, parts being broken away.

Fig. 2 is a similar view, showing flowers 40 in place and certain parts in different positions.

Fig. 3 is a plan of the upper end of the apparatus

Fig. 4 is a section on the line 4-4, Fig. 1.

Fig. 5 is a perspective view of a fragment 45 of the upper end of the apparatus.

In these views, A represents a downwardly and upwardly open tubular structure having, preferably, at its lower end outwardly projecting portions, shown in this instance as an integral flange A' to permit lifting the tube out of the earth, X, and the 50 whole is formed of material which is not readily corroded, e. g. galvanized iron. In this tube slides a similar tube B having on one side between its ends, a portion of its

wall removed to form an opening C extending approximately from side to side of the tube. Below the opening, this inner tube has a transverse member D to support a water receptacle E which is at will inserted and removed through said opening C, and at its upper end is provided with a fixed top F which may be integral or soldered in place. The top has a marginal flange G 65 around the body of the tube and a series of spaced inwardly extending fingers H which surround an open central space G' and are approximately radial, inwardly tapered, and provided with lateral vertical flanges 70 H' abutting the tube walls and enabling the fingers to resist downward pressure, such as is exerted by the weight of a person walking over the structure, especially since the flange G resists lateral movement of the tube 75 wall.

In this instance, both tubes are shown as cylinders. When desired, the inner cylinder may be raised as shown in dotted lines in Fig. 2 to expose its lateral opening above 80 the top of the outer cylinder, on which it rests at other times, and this upward movement is limited by a stud K, or the like, which projects from the outer cylinder through a slot B into said opening. When 85 so raised, the water receptacle E may be inserted, to rest upon the support D. The inner cylinder may then be lowered until the flange G rests upon the upper end of the outer cylinder or may be lowered a less 90 distance, to bring a notch B'' in its margin, into registry with the stud K, when a slight rotary movement of the inner cylinder causes the stud to engage in the notch and hold the inner cylinder raised to a distance depending upon the location of the notch or notches. 95

Preferably the height is such that the side opening in the inner cylinder will be a little below the top of its companion. Under such 100 conditions, rain will not carry a material amount of earth into the cylinders, nor throw earth upon the flowers, as it might were they not raised at all.

It may be noted that the pointed fingers 105 surrounding the central opening in the top aid in maintaining a pleasing arrangement of the flowers M.

If at any time it is desired to cut grass, for example, with a lawn mower, or to rake 110 the earth, this device will not materially interfere, for the flowers, if present may be

temporarily removed and the inner cylinder lowered until its top is flush with the surrounding earth. The flowers may be replaced later, of course. When it is not desired to display flowers, the inner cylinder is lowered as just suggested, and the flower receptacle, preferably of glass or metal, may rest concealed but always ready for instant use. It is important that no water can accumulate in the cylinders outside the receptacle, for various obvious reasons.

What I claim is:

1. The combination with an outer tube to be sunk in the ground in vertical position, of an inner tube slideable axially in the outer tube, and means for limiting the upward movement of the inner tube and preventing its separation from its companion.
2. The combination with a downwardly open flower-holder tube adapted to be sunk in the earth when in upright position, of a co-acting tube sliding vertically in the first and adapted to carry an enclosed flower receptacle, means for preventing the separation of the two tubes, and means for locking the inner tube at a predetermined height in the outer tube.
3. The combination with an outer flower holder member to be sunk in the earth to substantially its full length, of a co-acting inner tube cut away laterally to form on one side an opening, at some distance from each end, to insert and remove a flower receptacle, and means for preventing the separation of

the tubes, said inner tube being provided at 35 its upper end with means for holding, properly separated, flowers passing downward into said receptacle.

4. The combination with a flower-holder tube to be sunk in the ground to its full 40 length, of a co-acting inner tube laterally cut away between its end portions to form an opening for inserting a flower receptacle, provided below the opening with a support for such receptacle and at its upper 45 end with a flange to rest upon the outer tube, and a stop preventing the separation of the tubes while allowing the inner one to rise exposing said opening.

5. The combination with an outer flower-holder tube to be sunk in the ground, in vertical position, of a tubular receptacle telescoping with said tube and having between its ends a lateral opening to permit the insertion and removal of a water container when the receptacle is partially withdrawn from the outer tube.

6. The combination with a tubular flower-holder member to be permanently embedded, in upright position, in the ground, 60 of a co-acting member, adapted to contain a water receptacle, sliding vertically in the member first mentioned and having at its open upper end a series of marginally flanged, radial fingers.

In testimony whereof I hereunto affix my signature.

JOHN BUSS.
